UNITED STATES PATENT OFFICE.

RANDAL E. TALLEY, OF IRWIN, PENNSYLVANIA, ASSIGNOR TO GEORGE J. HAGAN COMPANY, OF PITTSBURGH, PENNSYLVANIA, A CORPORATION OF PENNSYLVANIA.

FURNACE.

1,362,369.

Specification of Letters Patent. Patented Dec. 14, 1920.

Application filed June 9, 1920. Serial No. 387,743.

To all whom it may concern:

Be it known that I, RANDAL E. TALLEY, residing at Irwin, in the county of Westmoreland and State of Pennsylvania, a citizen of the United States, have invented or discovered certain new and useful Improvements in Furnaces, of which improvements the following is a specification.

In an application filed October 4, 1919, Serial Number 328359, are described certain improvements in heating furnaces, said improvements being especially directed to so effecting the heating of the articles that they will not during such operation, be subjected to injurious gases. In said application the improvements are shown and described as embodied in a furnace for heating wire rods, sheets, etc.

The invention described herein which relates to the embodiment of such improvements in furnaces for heating a large variety of articles such as ax-heads, annular articles, etc., is hereinafter more fully described and claimed.

In the accompanying drawings forming a part of this specification, Figure 1 is a sectional elevation of a continuous furnace embodying the improvements claimed herein, the heating element being electrically heated; Fig. 2 is a transverse section of the same; Fig. 3 is a sectional plan view of a portion of the furnace; Figs. 4 and 5 are views similar to Figs. 1 and 2 illustrating certain improvements or modifications; Figs. 6 and 7 are detail views of portions of the conveying chain.

In the practice of the invention it is preferred that the furnace proper should be enclosed in a shell 26 formed of heat insulating material which will insure the stability of the structure and prevent the loss of heat. The furnace proper consists of a hearth 27 formed of refractory material and provided in its upper side with one or more troughs 28 having a depth and width proportional to the dimensions of the articles to be treated.

While the strip of metal forming the heating element may be given any desired form, it is preferred that it should be bent to form convolutions as shown in Fig. 3, thereby pro-

viding large heat radiating surface. These convolutions may be supported in any suitable manner closely adjacent to the path of movement of the articles along the trough or troughs which extend the entire length of the furnace. Supports for the convolutions may be conveniently formed by so widening the upper portions of the trough as to form ledges 30 on which the ends of the convolutions will rest. It will be observed that the convolutions extend back and forth across the portion of the troughs along which the articles are moved so that the articles will receive the heat directly from all of the strip except the small portions resting on the ledges. While not necessary it is preferred to interpose blocks or strips of material having high insulating capacity between the ends of the convolutions and the ledges.

The troughs are closed by blocks 32 of refractory material, adjacent edges of the blocks being supported by an abutment 33 intermediate the troughs, said abutment being preferably cut away at intervals so as to form openings between adjacent troughs for the equalization of the heat in the several troughs or tunnels as they may be properly termed, thus permitting the heating elements of the several tunnels to be connected to a common controller.

In order to move articles through the furnace the bottoms of the troughs or tunnels are slotted as at 34 for the traverse of suitable means for engaging the articles. Such means are connected to an endless chain 35 passing around sprocket wheels 36 arranged at opposite sides of the furnace and in such relation to the hearth that the article engaging devices carried by the chain will extend up through the slot 34 and engage the articles. The shafts of the sprocket wheels are mounted in suitable bearings 37 and one of the shafts is driven by a belt passing around a pulley 38 or by any other suitable means. The construction shown in Figs. 1 and 2 is designed to heat annular articles such as ring gears for automobiles, and the chain 35 is provided with suitable spaced pins 39 adapted to pass into the rings and move them along the tunnel into the discharge spout 40. In order to prevent injury

to the bottoms of the trough or tunnels, flat strips of metal 41 are arranged on the bottoms of the tunnels on both sides of the slot, as shown in Fig. 2.

- 5 In Figs. 4 and 5 is shown a construction of furnace for heating the edges of ax-heads for hardening or tempering. As shown in Fig. 5 the troughs formed in the hearth are provided with two slots 34^a and between these slots walls 42 are arranged to divide the trough in two relatively small tunnels, each having a slot therein. These walls will also serve as intermediate supports for the convolutions of the heating elements. In such 15 a construction the convolutions will extend across a plurality of tunnels. As in hardening and tempering ax-heads, only the portions of such heads at the cutting edges should be heated, the heads are so supported 20 by the means employed for moving them that only the portions to be heated will project through the slots into the tunnel. The walls of the slot are preferably of material of high heat insulating quality and are so 25 shaped and have such transverse dimensions that the sides of the slot will be in close proximity to the sides of the heads, thereby protecting the main portions of the heads from direct heating. The chain 35^b is so 30 constructed intermediate the pivotal connections of the links as to provide seats for the reception of the butt ends of the ax-heads and support the latter in a vertical position as shown in Figs. 6 and 7.
- 35 I claim herein as my invention:
1. A furnace having in combination a plurality of tunnels for the passage of articles to be heated, a heating element formed of a material capable of being raised to a 40 high temperature without the generation of gases injurious to the article being heated, arranged in such relation to the paths of movement of articles through the tunnels that heat will be radiated from said elements directly against the articles whereby a substantially uniform temperature may be maintained in the several tunnels, and means exterior of the tunnels for raising the temperature of the heating element.
- 45 2. A furnace having in combination a plurality of tunnels for the passage of articles to be heated, a heating element formed of a material capable of being raised to a high temperature without the generation of 50 gases injurious to the article being heated, arranged in such relation to the paths of movement of articles through a plurality of tunnels that the articles in each tunnel will be subjected to heat radiated from said element, said tunnels being so connected as to 55 permit an equalization of heat in the several tunnels, and means exterior of the tunnels for raising the temperature of the heating element.
- 60 65 3. A furnace having in combination a plu-

rality of tunnels for the passage of articles to be heated, a heating element so constructed and arranged that portions will extend across a plurality of tunnels and in operative proximity to the paths of movement 70 of articles through the tunnels, whereby substantially equal temperatures will be maintained in all the tunnels, and means exterior of the tunnels for raising the temperature 75 of the heating element.

4. A furnace having in combination a plurality of tunnels for the passage of articles to be heated, a heating element consisting of convoluted strips of metal supported in operative relation to the paths of movement 80 of the articles through a plurality of tunnels and means exterior of the tunnels for raising the temperature of the heating element.

5. A furnace having in combination a plurality of tunnels for the passage of articles to be heated, heating elements consisting of convoluted strips of metal, means for so supporting the heating elements that the convolutions will extend transversely of 90 the tunnels and above the paths of movement of the articles through the tunnels, and means exterior of the tunnels for raising the temperature of the heating elements.

6. A means for heating articles consisting of a tunnel through which the articles are passed, a heating element consisting of a convoluted strip of conducting material so supported within the tunnel that the portions of the convolutions will be at an angle 100 to the direction of movement of articles through the tunnel and an electric generator connected to the conducting element.

7. A means for heating articles consisting of a tunnel, means for moving articles continuously through the tunnel, a heating element consisting of an electrically heated convoluted strip of conducting material, the convolutions extending across the tunnel.

8. A means for heating articles consisting of a longitudinally slotted tunnel, means for moving articles along the tunnel, electrically heated convoluted strips of conducting material, and means for so supporting the conducting strip that its convolutions 115 will extend across the tunnel above the path of movement of the articles to be heated.

9. A furnace having in combination a tunnel for the passage of articles to be heated, means for moving articles through said tunnels, a heating element consisting of a plurality of substantially parallel members the opposite ends of each member being connected respectively to members on opposite sides thereof, said heating element being arranged above the path of articles through the tunnel and means exterior of the tunnel for raising the temperature of the heating element.

10. A furnace having in combination a

plurality of tunnels for the passage of articles to be heated, means for moving articles through said tunnels, a heating element consisting of a convoluted strip of metal so 5 constructed and supported that the convolutions extend across two or more of said tunnels and above the paths of movement of the

articles through the tunnels and means exterior of the tunnels for raising the temperature of the heating element. 10

In testimony whereof I have hereunto set my hand.

RANDAL E. TALLEY.
